UNITED STATES PATENT OFFICE.

GEORGE S. COLBURN, OF GARDNER, MASSACHUSETTS.

ATTACHMENT FOR CANE-SHAVING MACHINES.

SPECIFICATION forming part of Letters Patent No. 224,515, dated February 17, 1880.

Application filed July 12, 1879.

To all whom it may concern:

Be it known that I, GEORGE S. COLBURN, of Gardner, in the county of Worcester, and in the Commonwealth of Massachusetts, have invented an Improvement in Attachments for Cane-Shaving Machines, of which the following is a specification.

This invention has for its object the within-described means for adjusting the trimming and gaging disks in cane-shaving machines, whereby the disks may be revolved at intervals for the purpose of presenting a fresh cutting-edge to the work. In Patent No. 216,724, granted me June 27, 1879, I show one method of effecting this adjustment. The Patent No. 216,723, granted on the said date, describes another.

The construction herein shown and described is like that claimed in the patent to Jones, Smith, and Adams, No. 210,945, dated December 17, 1878.

Reference is had to the accompanying drawings, forming a part of the specification, in explaining the nature of my invention, in which—

Figure 1 is a perspective of the cutting-disk, its supporting-post, and operating-shaft; and Figs. 2, 3, and 4 are sections thereof, illustrating the construction. Fig. 5 is an elevation of the cutting-disk.

The cutting-disk A is supported upon the sleeve a, which has a bearing, b, in the post B, and the sleeve is further provided with a bevel or other gear, a'. The shaft C is provided with the worm c, and has a bearing in the said post B, and the worm is adapted to engage

with the gear a'. A pin, d, is arranged in the post B to project into a recess, a², in the face of the sleeve, and bears thereon sufficiently to prevent its being turned by any jar or concussion. The screw-stud a³, with an enlarged head, passes through the sleeve, fastens the cutting-disk thereon, and screws into a nut, a⁴, in the back of the post B.

The key or pin a⁵ locks the cutting-disk to the sleeve, so that it revolves therewith.

The head of the worm-shaft is provided with a thumb-piece, c'.

The post B is provided with a movement to and from the feeding-rolls similar to that given the post b in said Letters Patent No. 216,723.

In operation, by turning the worm-shaft the sleeve and disk are revolved on the stud a³, and as the shaft projects above the post it is brought within reach of the operator, and an adjustment of the disk can be made while the machine is in operation.

Having thus fully described my invention, I claim and desire to secure by Letters Patent of the United States—

1. The cutting-disk A, sleeve a, gear a', stud a³, and pin a⁵, in combination with the worm-shaft c, substantially as and for the purposes described.

2. The combination of the cutting-disk A, recessed sleeve a, gear a', stud a³, and pin d, in combination with the worm-shaft c, substantially as and for the purposes described.

GEO. S. COLBURN.
